BUILDING BLOCK

Philip E. Kopp, Ridgeleigh Drive, Minerva, Ohio

Filed Oct. 22, 1959, Ser. No. 58,022

Term of patent 14 years

(Cl. D18—2)

FIG. -1-

FIG. -2-

FIGURE 1

FIGURE 1 is a perspective view showing the front, top and one side of a building block embodying my new design;

FIGURE 2 is a perspective view on a reduced scale showing the back, top and other side thereof, and

FIGURE 3 is an enlarged fragmentary section taken from the broken line section of FIGURE 1.

The bottom of the ceramic building block is substantially like the top thereof.

I claim:

The ornamental design for a building block, as shown and described.
